UNITED STATES PATENT OFFICE.

HENRY BROWN, OF WASHINGTON, DISTRICT OF COLUMBIA.

RECEPTACLE FOR STORING AND PRESERVING PAPERS.

SPECIFICATION forming part of Letters Patent No. 352,036, dated November 2, 1886.

Application filed June 25, 1886. Serial No. 206,261. (No model.)

To all whom it may concern:

Be it known that I, HENRY BROWN, a citizen of the United States, residing at Washington, in the District of Columbia, have invented certain new and useful Improvements in Receptacles for Storing and Preserving Papers; and I do hereby declare the following to be a full, clear, and exact description of the invention, such as will enable others skilled in the art to which it appertains to make and use the same.

My invention relates to receptacles or cases for filing and preserving papers, and more particularly to a box adapted especially to receive the "carbon paper" sheets used in type-writing for reproducing copies.

The object of my invention is to provide a receptacle of such construction that the sheets of paper may be kept separate from each other, if desired, as well as out of contact with the cover of the receptacle, so that they are not only protected from injury and kept in perfect order, but are prevented from soiling the receptacle and cover, and, moreover, are rendered more accessible, so that single sheets may be extracted without risk of disarranging others. The receptacle as constructed by me is, however, capable of use as a means for preserving papers, letters, and documents of all kinds when it is desirable that such papers shall be readily accessible for reference.

I have illustrated the invention in the accompanying drawings, wherein like letters of reference indicate similar parts in the several views, and in which—

Figure 1 is a perspective view of the receptacle with the lid raised and one side and end partly broken away to show the interior construction. Fig. 2 is a longitudinal section of the receptacle with the lid or cover closed.

A represents a rectangular receptacle of box form, of suitable size, constructed preferably of paper-board, though wood, leather, or other material may be used, if desired. A flanged closely-fitting cover, B, is hinged to the back of the box and provided with straps b, for supporting it when raised. Within the receptacle is secured an inclined false back, C, to which is hinged a series of trays, D, as shown. Each of these trays is provided with longi-

tudinal raised ribs or flanges d, which extend from the front to the rear thereof, the ribs being placed so as to leave a projecting ledge, d', of the tray upon each side, Fig. 1, which may be utilized in forming an index, as shown. 55 The number of these trays is of course dependent upon the desired capacity and the depth of the receptacle and the space to be allowed for each tray.

The carbon papers or other documents to be preserved are placed in the trays, and it will be seen by reference to Fig. 1 that the ribs separate the trays, so that the sheets are kept apart and out of contact with any part of the receptacle. Each tray is provided with a 55 strap, d'', for lifting it. When the cover of the receptacle is raised, the trays can be lifted separately, and, owing to the inclined shape of the false back, any number of them may be raised at once without interference, since 70 they are hinged far enough apart to clear each other, and still maintain their relatively parallel position. The bottom E of the receptacle is also provided with ribs or flanges e, so that it may also act as a compartment for the 75 same purpose as the hinged trays. The blank space on the inside of the cover may also be utilized as a general index, as indicated in the drawings.

As thus constructed my receptacle affords a 80 neat and compact portable case, especially adapted for filing carbon papers, for which, so far as I am aware, no special provision has been made; but, whatever may be the character of the contents, it is evident that papers 85 may be perfectly filed and protected, and yet any of them be withdrawn without disturbing or disarranging the others.

Having thus described my invention, what I claim as new, and desire to secure by Letters 90 Patent, is—

1. In a receptacle adapted to be used as set forth, the combination of a box having a bottom provided with longitudinal strips with a series of hinged trays within the box, each of 95 such trays having a longitudinal rib or strip placed inside the edge of the tray so as to leave a portion of the tray projecting on each side beyond said strip, substantially as described.

2. In a receptacle adapted to be used as set forth, the combination of a box, A, having an inclined false back, C, a series of trays, D, hinged to said back, having longitudinal raised ribs d , so mounted as to leave projecting ledges d' on each side thereof, suitable straps, d'' , for lifting the trays, and a hinged cover, B, substantially as described.

In testimony whereof I affix my signature in the presence of two witnesses.

HENRY BROWN.
